UNITED STATES PATENT OFFICE.

WALTER E. VERKLER, OF CHICAGO, ILLINOIS.

PRINTING MACHINE.

Application filed March 31, 1923. Serial No. 628,984.

To all whom it may concern:

Be it known that I, WALTER E. VERKLER, a citizen of the United States, and a resident of Chicago, county of Cook, and State 5 of Illinois, have invented certain new and useful Improvements in Printing Machines, of which the following is a specification.

My invention relates to improvements in printing machines and has for its principal 10 object the provision of an improved construction of this character which will be highly efficient in use.

Among other objects of the invention is the provision for checking the speed of rotation of the printing drum of the machine 15 so that the speed of rotation will be uniform when the printing drum is operated.

Other objects of the invention will appear hereinafter.

20 The invention consists in the combinations and arrangements of parts hereinafter described and claimed.

The invention will be best understood by reference to the accompanying drawings 25 forming a part of this specification and in which,

Fig. 1, is an elevational view of a printing machine embodying the invention;

Fig. 2, is a sectional view taken substantially on line 2—2 of Fig. 1;

Fig. 3, is a sectional view taken substantially on line 3—3 of Fig. 1;

Fig. 4, is a fragmentary side elevational view of the invention showing the brake 35 mechanism associated therewith, and

Fig. 5, is a fragmentary sectional view taken substantially on line 5—5 of Fig. 4.

Referring to the drawings 9 and 10 indicate the end frames of the printing machine 40 A, 11 indicates the printing drum, 12 indicates the operating handle and 13 indicates a part of the paper feeding mechanism.

The printing drum 12 carries the usual 45 removable printing cylinder 14 over the outer surfaces of which a ribbon, not shown, is passed and carried by rollers 15. The printing cylinder 14 is a segmental plate semi-circular in cross section and is mounted on the printing drum in the usual manner. At one side 16 of the printing drum 50 and directly beneath the printing cylinder

are web members 17 of substantial thickness that serve as counterbalances.

The above structure so far set forth is embodied in most printing machines of the 55 approved type and constitutes no part of the present invention, these parts being merely mentioned so that the invention will be more fully hereinafter understood.

In carrying out the objects of my invention I provide an additional counterbalance which is mounted on the opposite side 18 of the printing drum and on the side of the drum farthest away from the printing cylinder, said counterbalance being indicated 60 at 19 and is fixed to the end 18 of the printing drum by suitable screws 20. This counterbalance is preferably equal to the weight of the counterbalance 17 and is capable of 65 equalizing the rotation of the printing 70 drum when the printing cylinder is removed therefrom. This provision of the additional counterbalance also serves to facilitate the mounting of the printing cylinder on the printing drum by reason of the 75 fact that the additional weight balances the printing drum when idle and therefore will not have the tendency to rotate during the mounting of the printing cylinder on the printing drum by reason of having a 80 greater weight on one side of the axis of rotation than the other.

When the printing cylinder is mounted on the printing drum and when the drum is rotated, the printing cylinder during downward rotation due to its own weight, will naturally increase the speed of the printing 85 drum. I therefore aim to regulate the speed of the printing drum so that the same will be uniform and I accomplish this object by 90 providing a brake mechanism, the construction and arrangement of which is as follows:

Referring especially to Figs. 4, 5, 21 indicates an arm fixed to the end frame 10 of the machine A by suitable screws 22 and having a bent portion 23 which is bent inwardly in spaced relation with the peripheral edge 24 of the end frame 10. The bent end 23 carries a vertical arm 25 having spaced threaded openings 26 formed therein. A brake shoe is indicated at 27

and carries a brake lining 28 of suitable material such as leather or the like and is adjustably carried by set screws 29 threaded through the openings 26 and having heads 30 mounted for free rotation in recesses 31 formed in the brake shoe 27. It will be seen by manipulating the set screws 29 that the brake shoe can be adjusted away from or toward the arm 25.

10 In most approved types of printing machines there is provided a band, which in this instance is indicated at 32 and extends around the printing drum 11 at one end thereof, this band is used in connection with 15 other mechanism for regulating the feed of the paper through the machine and is provided with elevated portions 33 which extend half-way around the printing drum adjacent the place where the printing cylinder is mounted. The brake shoe 27 is 20 adapted for engagement with the peripheral elevated side of this band and as already indicated, the brake shoe can be adjusted toward or away from the peripheral 25 side of the band.

Inasmuch as the printing cylinder is mounted on the side of the printing drum opposite that where the elevated portion is located it will be seen that upon rotation of 30 the drum and during the downward movement of the printing cylinder the elevated portion will engage the brake shoe lining and thereby be prevented from increasing speed of rotation thus checking such increase of speed that would be otherwise brought about by the weight of the printing cylinder.

It will be apparent from the description herein that I provide a construction or an 40 attachment to a printing machine designed especially to keep the speed of the printing drum uniform during operation and by doing so I prevent the loss of a large amount of paper which is damaged by the blurring 45 of the print thereon due to the increased speed of the printing drum brought about by the printing cylinder when the cylinder travels downwardly during rotation.

It will also be apparent that the structure 50 herein is simple and can be manufactured as an attachment at an economical cost.

While I have illustrated and described the preferred form of construction for carrying my invention into effect, this is 55 capable of variation and modification without departing from the spirit of the invention. I, therefore, do not wish to be limited to the precise details of construction set forth but desire to avail myself of such 60 variations and modifications as come within the scope of the appended claims.

Having described my invention what I claim as new and desire to secure by Letters Patent, is:

65 1. In combination with a printing drum

carrying a printing cylinder semi-circular in cross section and having a counterbalance at one end adjacent the printing cylinder, a second counterbalance at the other end of the drum opposite the printing cylinder, and means for regulating the speed of rotation of the drum.

2. In combination with a printing drum carrying a printing cylinder semi-circular in cross section and having a counterbalance 75 at one end adjacent the printing cylinder, a second counterbalance at the other end of the drum opposite the printing cylinder, and adjustable means for regulating the 80 speed of rotation of the drum.

3. In combination with a printing drum carrying a printing cylinder semi-circular in cross section and having a counterbalance at one end adjacent the printing cylinder, a second counterbalance at the other end 85 of the drum opposite the printing cylinder, and a brake shoe for engagement with the drum adapted to regulate the speed of rotation of the drum.

4. In combination with a printing drum carrying a printing cylinder semi-circular in cross section and having a counterbalance at one end adjacent the printing cylinder, a second counterbalance at the other end of the drum opposite the printing cylinder, 95 and an adjustable brake shoe for engagement with the drum adapted to regulate the speed of rotation of the drum.

5. In combination with a printing machine including end frames, a printing drum carrying a printing cylinder semi-circular in cross section and having a counterbalance at one end adjacent the cylinder, a second counterbalance at the other end of the drum opposite the cylinder, a bracket carried by 100 one of the end frames and having a bent portion in spaced relation with the edge of the frame, a brake shoe carried by the bracket for engagement with the drum to regulate the speed of rotation of the drum.

6. In combination with a printing machine including end frames, a printing drum carrying a printing cylinder semi-circular in cross section and having a counterbalance at one end adjacent the cylinder, a second counterbalance at the other end of the drum opposite the cylinder, a bracket carried by one of the end frames and having a bent portion in spaced relation with the edge 105 of the frame, and an adjustable brake shoe carried by the bracket for engagement with the drum to regulate the speed of rotation of the drum.

7. In combination with a printing drum carrying a printing cylinder semi-circular in cross section and provided with a band provided with an elevated portion and having a counterbalance at one end thereof adjacent the printing cylinder, and means 120 for engagement with the elevated portion 125 130

of the band for regulating the speed of rotation of the drum.

8. In combination with a printing drum carrying a printing cylinder semi-circular in cross section and provided with a band provided with an elevated portion and having a counterbalance at one end thereof adjacent the printing cylinder, a second counterbalance at the other end of the drum opposite the printing cylinder, and means for

engagement with the elevated portion of the band for regulating the speed of rotation of the drum.

In testimony whereof I have signed my name to this specification in the presence ¹⁵ of two subscribing witnesses.

WALTER E. VERKLER.
